UNITED STATES PATENT OFFICE.

GEORGE H. WAHLER AND LUTHER H. LEBER, OF LITTLESTOWN, PENNSYLVANIA, ASSIGNORS TO SAID LUTHER H. LEBER.

COIN-COUNTER.

SPECIFICATION forming part of Letters Patent No. 340,392, dated April 20, 1886.

Application filed November 16, 1885. Serial No. 182,938. (No model.)

To all whom it may concern:

Be it known that we, GEORGE H. WAHLER and LUTHER H. LEBER, citizens of the United States, residing at Littlestown, in the county 5 of Adams and State of Pennsylvania, have invented certain new and useful Improvements in Coin-Counters; and we do hereby declare that the following is a full, clear, and exact 10 description of the same, reference being had to the annexed drawings, making a part of this specification, and to the letters and figures of reference marked thereon.

Figure 1 of the drawings is a sectional elevation of our invention; Fig. 2, a longitudinal 15 section taken on line $\alpha\alpha$ of Fig. 1; and Fig. 3, a detail view, in perspective, of the push-key and horizontal slide, showing them connected together by the lever-rod.

The present invention has relation to certain 20 new and useful improvements in that class of devices used to facilitate the making of change, and to admit of the coins being secured within holders adapted to the different values; and it consists in the details of construction, substantially as shown in the drawings and hereinafter described and claimed.

In the accompanying drawings, A represents a suitable inclosing-case provided with a series of holders, B, of various diameters, to 30 adapt them to coins of different denominations—such as five-cent pieces, dimes, quarter-dollars, &c.—the tubes being of any desired number, according to the capacity of the device, and of any suitable length.

In place of making the coin-holders B independent of each other, which greatly increases 35 the cost of manufacture, they are formed out of a solid rectangular block, C, of wood, or other suitable material, and secured within the case A to the sides thereof. A common 40 chute, D, serves the purpose of all the coin-holders, to receive the coin therefrom and conduct it to the discharge-opening a, where it falls into the person's hand held there to receive it.

Through the top of the case A, directly over each coin-holder B, is an elongated slot, through which the coins are dropped.

Each coin-holder B at its base has a space, 50 b, of sufficient size to allow the bottom one of

the end coins of the pile to be pushed out onto the chute D by a slide consisting of a rectangular plate, E. In place of making the end of the plate straight, or forming it with a round opening into which the coin fits when dropping from the holder, we simply form it with a crescent-shaped end, c, which embraces a portion only of the edge of the coin sufficient to carry it along in a straight line and prevent it from moving laterally, as would be 60 the case were the end perfectly straight, and where a circular opening is used in the plates it requires a nicety of action of the plate to bring the opening therein on a true line under the coin-holder. 65

The platform F, which projects inwardly from the coin-holders, has guides d for the sliding plates E, said plates being connected to push-buttons, knobs, or keys G, as shown.

The connection of the sliding plates E with the keys G is made by the rod H, which we shall term a "lever-rod," the upper end of said rod being attached to the key and extending down through a hole in the rear end of the plate, so that when the key is pressed down by means 70 of the rod-connection the plate will be forced forward and carry with it the bottom one of the coins.

The keys are loosely mounted on a stationary transverse rod, e, and after the key has 80 been pressed down the parts are restored to their normal position by a suitable spring, either rubber or metal.

In the present instance we have shown a flat or round curved spring, I, one end being 85 attached to the block C, and the opposite or free end bearing in a groove, f, formed on the under side of each key.

To allow the lever-rod H to be projected forward, an elongated slot, g, is formed in the 90 platform F, through which the rod extends.

If preferred, a chute and discharge-opening may be provided for each one of the coin-holders in place of a single one, as shown.

It will be noticed that the device as constructed is very simple, there being fewer parts, and consequently they are less liable to get out of order, the usual bell-crank levers, rods, and coiled springs for operating the push-plates being dispensed with. 95

Having now fully described our invention, what we claim as new, and desire to secure by Letters Patent, is—

A device for holding and delivering coins, consisting of the following elements, viz: an inclosing-case having a chute and delivery-opening, a series of coin-holders formed from a solid rectangular block, a platform having elongated slots and flanged guides, a series of sliding plates supported thereby, a series of pivoted keys or buttons and springs acting thereon, and rods attached at one end to the buttons and extending down through perfora-

tions in the sliding plates and through the elongated slots in the platform, and operating to force the plates forward upon depressing the keys or buttons, substantially as and for the purpose set forth.

In testimony that we claim the above we have hereunto subscribed our names in the presence of two witnesses.

GEORGE H. WAHLER.
LUTHER H. LEBER.
